UNITED STATES PATENT OFFICE.

THADDEUS C. BEATTY, OF GRINNELL, IOWA.

CHICKEN-ROOST.

1,371,216.

Specification of Letters Patent. Patented Mar. 15, 1921.

Application filed February 13, 1920. Serial No. 358,366.

To all whom it may concern:

Be it known that I, THADDEUS C. BEATTY, a citizen of the United States, and residing at Grinnell, in the county of Poweshiek and 5 State of Iowa, have invented certain new and useful Improvements in Chicken-Roosts, of which the following is a specification.

My invention relates to chicken roosts, 10 and more particularly to roosts constructed to receive and dispel therefrom as needed a liquid disinfectant.

Among the objects of my invention is to provide an improved roost for fowls, adapted to contain therein, and dispel therefrom, a liquid disinfectant; to protect the chickens and other fowls from vermin, lice, mites and insects; further to provide a poultry roost which will contain sufficient amount 20 of the disinfectant within the container, and properly protected from dust, dirt and the like, but capable of transmitting the disinfectant in the shape of oil or gas, to the exterior of the roost, where it will kill, or 25 drive away vermin, but which will permit of sufficient of the disinfectant to reach the outer covering, so the chickens or other fowl roosting on the perch will get the same on their feet, and thereby permit the fumes to 30 pass into their feathers; further to provide extensible supporting elements at both ends of the roost, which may be pushed in or out, so that the roost may be shipped with the ends pushed in, and when received by the 35 purchaser may be pulled out and be adjustable to different lengths desired; and such further objects, advantages, and capabilities as will later more fully appear.

My invention further resides in the novel 40 construction, combination and arrangement of parts illustrated in the accompanying drawing, and while I have shown therein a preferred embodiment, I desire it to be understood that the same is to be considered as 45 illustrative only, and not as limiting my invention.

In the drawings, Figure 1 is a perspective view of the roost;

Fig. 2 is a fragmentary plan view of the 50 same, having parts of the outer covering and metal container removed;

Fig. 3 is a longitudinal vertical section of a portion of the roost, showing in elevation the wire ends in closed position, and in 55 dotted lines in extended position;

Fig. 4 is a transverse vertical section

showing the slot of the metal container, surrounded by the outer covering;

Fig. 5 is a view similar to Fig. 4, but taken on a plane passing through opening 8 60 hereinafter referred to.

Fig. 6 is a view similar to Fig. 4, showing depending flanges of the outer covering.

Referring to the drawings. The roost 1 consists of a metal container 2, shaped like a 65 long tube, having at its upper edge a longitudinal slot 3 running lengthwise of the roost. It is preferable to have the edges of the longitudinal slot serrated as shown at 4, but they may be modified to any other acceptable contour. The metal tube is provided with stoppers 5, to seal the ends of the tube, to hold the contents therein. These stoppers may be made of wood or other suitable material. The roost is also provided 70 with an outer tube or wrapper 6, which entirely surrounds the tube. This outer wrapper may be made of thin strips of wood or veneer, or other suitable substance. A strip of wood 7 is inserted in the slot, and extends 75 to the bottom of the inner container 2. Such strip is gripped by the serrated teeth 4 of the slot, and held in contact with the outer covering 6, or one edge, or both edges of the outer wrapper, may if desired, be inserted in 80 the longitudinal slot 3 between the serrated edges thereof, and may be of such length that they will reach to the bottom of the interior of the metal tube 2. This is shown in Fig. 6. It will then be seen that the longitudinal slot of the metal tube is thereby 85 closed, and the contents thereof are protected from dust and dirt, and the like, entering therein. A small opening 8 is provided in the metal tube at the top thereof, 90 and adjacent to the longitudinal slot 3, where liquid material may be poured into the roost. A wire coil, cord, or other suitable material 9 is bound around the outer wrapper 6, the entire length of the tube to 95 bind the two tubes together and to provide a better perch for the fowls roosting thereon.

Additional binding and holding means are provided by bands 10 at either end or other part of the tube. These bands are adjusted 100 by screws 11, and a nut 12. The roosts are provided with adjustable wire ends 13, the arms of which are adapted to pass through, or by the end blocks 5. These wire ends may be pushed in when the roost is being shipped 110 or handled, and may be pulled out to variable lengths to adapt the roost to be at-

tached to racks or foundations of different widths.

When the roost is placed in position using the extensible wire ends to adjust it to the exact space available, liquid disinfectant, insecticide or germicide, or the like, is poured into the interior metal container, through the small opening. A portion of the liquid will be absorbed by the depending strip 7, or in the form shown in Fig. 6 by flanges 7^a from the outer wrapper of wood, and will be carried to the wood wrapper on the outside of the metallic tube, such depending strips of the outer wrapper being held in place by the teeth of the serrated edges of the longitudinal slots and will also act to completely cover the metal tube, except at the small opening provided for insertion of the liquid. The effect of the liquid disinfectant, insecticide or germicide absorbed by said outer wrapper will be to kill, or drive off lice, mites and other vermin. The fumes of such disinfectant will also pass into the feathers of the fowl to serve a similar purpose. The wick-like action of the strip 7, or the depending flanges of the covering 6 in Fig. 6, will also carry enough of the liquid to the outer wrapper to allow the disinfectant to get on the feet and legs of the fowls, and will tend to keep such fowls free from vermin.

Having now described my invention, I claim:

1. In a device of the class described, a metal container, an outer covering of absorbent material, for the absorption of the contents of said container, and wick-like means for transferring said contents from the container to the covering and to support and strengthen said container, said outer wrapper surrounding and inclosing such metal container, except for a small aperture wherein the contents of said container are inserted.
2. In a device of the class described, a metal container, having running along the top thereof, a longitudinal slot, an outer wrapper or container having depending edges adapted to be inserted in said slot, and to completely fill said slot, except at an aperture for the insertion of the contents of said metal container, said outer wrapping being constructed of material capable of absorbing and carrying moisture.
3. In a device of the class described, a metal container provided at the top thereof with a longitudinal slot having serrated edges, an outer covering of absorbent material, a strip of absorbent material inserted in said longitudinal slot, and reaching to the bottom of said inside metal container, said outer covering inclosing said inner container, except for a small aperture in

which the contents of said metal container are inserted.

4. A chicken roost consisting of a metal tube, having a longitudinal slot, stoppers to be inserted in the ends of said tube, an outer tube of absorbent material, a wick-like extension of said outer wrapper, extending in said metal container, through said longitudinal slot, and adapted to completely close said slot, except for a small aperture at the top of said roost for the insertion of the contents in said metal tube and bands adapted to hold said tubes in compact engagement with said stoppers.

5. A roost comprising an inner metal tube, adapted to hold a liquid disinfectant, a small opening in said tube for the insertion of said liquid disinfectant; a longitudinal slot running lengthwise of said tube; an outer wrapper of absorbent material, wick-like means entirely inclosed by said outer wrapper and extending therefrom through the wall of the metal container to the bottom thereof; means for binding said tubes together.

6. In a device of the class described, a metal tube with end blocks to close the ends of said tube, a longitudinal slot running the length of said tube, having serrated edges; an outer wrapper of absorbent material with depending edges adapted to be inserted within said horizontal slot and reaching to the bottom of said metal tube, said outer wrapper completely surrounding said metal tube except at a small aperture wherein the contents of said metal tube are inserted; a binder coiled around said outer wrapper; a small binder at each end of the roost, and adjustable wire grips capable of being extended through said end slot.

7. In a device of the class described, a metal container, having an opening for the insertion of the contents thereof having running along the top thereof a longitudinal slot, an outer wrapper or container of absorbent material, for the absorption of the contents of the container, and wick like means to transfer the contents from the container to the outer wrapper and to support and strengthen said container, said means being entirely within said outer wrapper and extending therefrom through the wall of the metal container to the bottom thereof and completely filling said slot except the opening for the insertion of the contents of said container.

In witness whereof I hereunto subscribe my name to this specification in the presence of two witnesses.

THADDEUS C. BEATTY.
